ALFRED F. MASURY, WILLIAM B. JUPP, AND ROBERT G. ANDERSON, OF NEW YORK, N. Y., ASSIGNORS TO INTERNATIONAL MOTOR COMPANY, OF NEW YORK, N. Y., A CORPORATION OF DELAWARE

INTERNAL-COMBUSTION-ENGINE COOLING SYSTEM

Application filed October 3, 1927. Serial No. 223,629.

The present invention relates to cooling systems of the type used on vehicles and is applicable, particularly, to rail car constructions where considerable heat is to be dissipated due to the large amount of power which is required to be generated. In constructions of this type it is desirable that the outer sides of the vehicles be free from projections and have a surface, the greater part 10 of which is unbroken in continuity.

Consideration of these features in connection with the problem of providing adequate cooling facilities for the engine has resulted in the invention embodied herein, an object 15 of which is to incorporate in the body of a rail car, a radiator which has supplied there-to an adequate current of cooling air, the radiator being suitably positioned within the body.

20 A further object of the invention is to utilize the head wind for cooling the radiator without obstructing the front of the car, the construction being such that when the car is traveling rearwardly, a vacuum will be created in such relation to the cooling apparatus that a sufficient reverse current to effect the cooling will be effected.

In addition to the above objects, the present invention contemplates embodying with 25 the above features a second radiator to which currents of air are conducted by suitable eductors associated with the exhaust of the engine. These elements are mounted to take air from the side of the car so that the water in the cooling system will initially flow 30 through the roof radiator to be cooled thereby, and then pass to the second radiator which is cooled by air drawn from the side 35 of the car by the eductor.

40 Other objects will appear as the invention is set forth in detail and reference will now be had to the accompanying drawings for a more detailed description of the invention, 45 wherein:

Figure 1 is an elevation illustrating the cooling system of the present invention and showing the disposition of the roof and side radiators and the paths taken by the cooling 50 air in each case.

Figure 2 is a side elevation of the device shown in Figure 1.

Figure 3 is an elevation of a modified form of the invention wherein the side radiators are removed from the sides of the car and 55 constructed to take air from beneath the roof radiators.

Figure 4 is a side elevation of the construction shown in Figure 3.

Referring particularly to Figures 1 and 2, *a* indicates an internal combustion engine of desired form provided with a water pump *b* which circulates cooling water through the engine and out pipe *c* and *c'* to a roof radiator *d*. The path taken by this cooling medium is indicated by dotted arrows in the figures. This radiator is constructed to conform, generally, with the outline of the roof of the car and is relatively shallow, the greatest width being presented to the atmosphere in order 60 that the air may pass through the shallow dimension. Lying, as it does, flush with the roof line of the car, all head resistance is eliminated due to projections above the roof of portions of the radiator. From the roof 65 radiator the cooling medium is conducted through pipe *c''* to a side radiator *e*, a collecting tank *f* and through pipe *c'''* back to the pump *b*. The collecting tank serves to drain 70 the radiators when the engine is not running, thus preventing freezing thereof during cold weather and rendering the use of an anti-freezing mixture unnecessary. The pump *b* is designed to give insufficient head to the water to circulate it through the radiators 75 when the engine is idling and, if desired, a by pass may be supplied to permit the circulation of the liquid without passing through the radiators. In this manner the radiators are protected during extremely cold weather 80 when the flow of the cooling liquid is inadequate to prevent the freezing thereof. This construction insures a hot engine at 85 idling speed and prevents the exposure of the water to the cold air at low speeds.

The car is constructed with a visor *g* which catches the head wind, when the car is in motion forwardly and forces it into the chamber *h* beneath the roof radiator *d*. From this 90 chamber the air passes upwardly through the 100

roof radiator and out at the top of the car as indicated by the solid arrows in Figure 2. It will be quite apparent that if the car is moving rearwardly the suction created by that portion of the car under the visor will cause the air to be drawn downwardly through the roof radiator and its path reversed in this manner. The reversed solid arrows indicate this path.

10 The direction of the flow of air through the radiator can be controlled regardless of the direction of movement of the car by controlling the pressure differential between the sides of the radiator. To do this baffles are 15 placed at suitable points on the vehicle to create regions of high and low pressure which induce the desired flow.

10 The side radiator *e* is cooled by means of an eductor construction which utilizes the 20 Venturi effect of the exhaust gases of the engine. The path of the exhaust gases is indicated by dot and dash arrows, and consists of the pipe *i* and *i'* leading the gases to a plurality of Venturi throats *i²* and out 25 through the top of the car *i³*. About these Venturi throats is a housing *j* which restricts the flow of air through the eductor and communicates with an enclosure *j'* about the side radiator *e*. This enclosure in turn communicates with the outside of the car through 30 openings *j²* and in this manner, cooling air is drawn from the side of the car, through enclosure *j'*, and housing *j*, and expelled through the top of the car at *i³*. The path 35 of such air is indicated by solid arrows in Figure 1.

If desired, a jacket *k* may be provided for the exhaust pipe *i'*, and constructed to communicate with the housing *j*. With this construction, the exhaust gases also serve to ventilate the interior of the cab and maintain it at a desired temperature.

In order that the engine and generator unit may be cooled more effectively, and at the 45 same time a means provided for draining the engine exteriorly of the car, a drain valve and pipe *b'* are provided, the pipe discharging into a tube *b²* secured to the under portion of the car. The tube may, in turn, discharge at any desired location with respect 50 to the wheels or other structure under the car body and at the discharge end scoops *b³* are formed, facing in either direction. In this manner, air will be deflected into the 55 tube *b²* and carried into the cab under the power units, thus serving to cool the under portions thereof.

The usual auxiliary heating plant *f'* for heating the car in cold weather is provided 60 with a coil *f²* which connects to a coil *f³* in the collecting tank *f*. By means of valve *f⁴*, the collected water may be heated from the plant *f'* in cold weather to aid in starting as well as serving to heat the car when the 65 plant is shut down in seasons of the year

when a slight heating may be desirable. This also serves as an additional cooling means for the water of the cooling system. The water supply is obtained from a reservoir *l* through a pipe line *l'*.

Within one of the pipes of the upper bank 70 of the radiator a drain pipe *m* is provided having apertures therein and a downwardly extending end *m'* in the header and pipe *c²*. When the system is being used and water passes through the lower bank of pipes, a suction will be produced in the pipe *m* due to the resulting flow about the end *m'*. This will remove the air from the upper bank and facilitate its filling with water. Likewise, 75 when the system is being drained, pipe *m* will enable air to be supplied to the upper portion thereof and thus permit the water to be drained off quickly.

80 Figures 3 and 4 show a modified form of the invention, wherein the side radiators *e* are moved to the center of the cab, and enclosure *j'* formed in the nature of a continuation of housing *j*. Instead of communicating with the exterior of the cab through 85 openings *j²*, the enclosures communicate through openings *j³* with the chamber *h* beneath the roof radiators. In this construction, if the car is standing still, the roof radiators will be rendered more effective 90 than in the construction shown in Figures 1 and 2, since the air drawn through the side radiators *e* will pass through, or under, the roof radiators *d*.

95 The above description sets forth a cooling system which is effective under all conditions, the visor *g* serving to catch the head wind and force it through the roof radiator in Figures 1 and 2, and the roof and side radiators in Figures 3 and 4. When the car is moving in the reverse direction, the vacuum created under the visor will create a reverse 100 flow of air and in this manner effectively cool the radiators, and when the car is standing still, the exhaust through the Venturi 105 eductor causes a flow of cooling air through the side radiators as well, in Figures 3 and 4, as through the roof radiators. Although the invention has been described with reference to the specific constructions shown 110 herein, it is obvious that the parts may be rearranged and designed in other ways, and the invention is not to be limited save as defined in the appended claims.

115 120 What we claim is:

1. A cooling system for vehicles comprising means to carry a radiator at the top of a vehicle, means to conduct a cooling medium to the radiator, and a visor formed by a continuation of the top of the vehicle 125 the profile of the visor conforming to the profile of the top to cause the cooling medium to flow through the conducting means.

2. A cooling system comprising means to carry a radiator in the roof of a body of a 130

vehicle with the upper side thereof exposed to the atmosphere and conforming to the profile of the top of the roof, and means to cause cooling air to flow through the radiator.

5 3. A cooling system comprising means to mount a radiator on the roof of a body of a vehicle, a visor formed by an extension on the top thereof, means to cause a flow of air through the visor and the radiator, and means to cause the other side of the radiator to communicate with the atmosphere through the roof of the vehicle.

10 4. A cooling system for a vehicle comprising a plurality of adjacent radiators disposed in intersecting planes, means to cause air to flow in one path through one of the radiators, and means to cause a flow of air through the other radiator in a different

20 5. A cooling system for a vehicle comprising a roof radiator, a side radiator, means to cause air to flow through one of the radiators, and means to cause a flow of air through the other radiator.

25 6. A cooling system for a vehicle, comprising a plurality of radiators, means to cause air to flow through one of the radiators, means to cause the one side thereof to communicate with the atmosphere through the roof of the vehicle, and means to cause a flow of air through the other radiator.

30 7. A cooling system for a vehicle comprising a plurality of radiators, eductor means associated with the engine exhaust of the vehicle, means associated with the eductor and one of the radiators to cause air to flow therethrough, and other cooling means to cause air to flow through another of the radiators.

35 8. A cooling system for a vehicle, comprising a roof radiator, a side radiator, eductor means associated with the engine exhaust of the vehicle, means associated with the eductor and one of the radiators to cause air to flow therethrough, and means to cause air to flow through the other radiator from the outside of the vehicle.

40 9. A cooling system for vehicles comprising a roof radiator, side radiator, means to cause the air to flow through the roof radiator in streams parallel to the vehicle, means to permit the cooling air to flow through the roof of the vehicle, eductor means associated with the engine exhaust of the vehicle, and means associated with the eductor and the side radiator to cause air to flow therethrough.

45 10. In a roof radiator construction for a rail car, a false roof conforming to the profile of the top of the car, a radiator formed therein and communicating with the atmosphere through the false roof, and a true roof under the false roof forming a ventilating passage for the cooling air passing through the radiator.

11. In a roof radiator construction for a rail car, a radiator, and means for mounting the radiator within the roof with its upper surface exposed to the atmosphere and flush with the roof line, whereby head resistance offered thereby is eliminated.

70 12. In a vehicle having a roof provided with an opening therein, a radiator disposed in the opening flush with the profile of the roof and having its largest superficial radiating surface exposed to the atmosphere.

75 13. In a vehicle having a roof provided with an opening therein, a radiator disposed in the opening flush with the profile of the roof and having its largest superficial radiating surface exposed to the atmosphere, and means to circulate cooling air through the radiator by movement of the vehicle.

80 14. In a vehicle having a roof provided with an opening therein, a radiator having a long and short dimension and disposed horizontally in the opening and flush with the profile of the roof.

85 15. In a vehicle having a roof provided with an opening therein, a radiator having a long and short dimension and disposed horizontally in the opening and means to circulate cooling air through the radiator in the direction of the short dimension.

90 16. In a vehicle having a roof provided with an opening therein, a radiator having a long and short dimension and disposed horizontally in the opening whereby its top surface of greatest radiating extent is exposed to the atmosphere, and means to circulate cooling air upwardly through the radiator.

95 17. In a vehicle having a roof provided with an opening therein, a radiator having a long and short dimension and disposed horizontally in the opening whereby its top surface of greatest radiating extent is exposed to the atmosphere, and means to circulate cooling air upwardly through the radiator by movement of the vehicle.

100 This specification signed this 20th day of June, A. D. 1927.
